UNITED STATES PATENT OFFICE.

EVERT E. SWIFT, OF CHILLICOTHE, ILLINOIS.

RAIL JOINT.

Application filed July 20, 1923. Serial No. 652,744.

To all whom it may concern:

Be it known that I, EVERETT E. SWIFT, a citizen of the United States, residing at Chillicothe, in the county of Peoria and State of Illinois, have invented certain new and useful Improvements in Rail Joints, of which the following is a specification.

This invention relates to certain new and useful improvements in railway joints of the type employing joint chairs integrally formed on fish plates.

An object of the invention is to provide a joint of the above kind by means of which longitudinal creeping of the rails will be effectively prevented, whereby a relatively large lateral bearing is had upon the ties for preventing lateral tilting or displacement of the rails, whereby the usual objectionable pounding at the meeting rail ends is substantially eliminated, and through the use of which the above beneficial results are obtained in a simple and efficient manner.

Another object of the invention is to provide a device embodying the above features in an extremely simple and durable construction of parts capable of being expeditiously applied by unskilled labor and capable of being manufactured at an extremely low cost.

With the above general features in view, and others that will become apparent as the nature of the invention is better understood, the same consists in the novel form, combination and arrangement of members hereinabove more fully described, shown in the accompanying drawings and claimed.

In the drawings, wherein like reference characters indicate corresponding parts throughout the several views,

Figure 1 is a top plan view of a rail joint constructed in accordance with the present invention.

Figure 2 is a side elevational view thereof.

Figure 3 is an enlarged transverse sectional view taken substantially upon line 3-3 of Figure 1.

Figure 4 is a perspective view of one of the combined joint chairs and fish plates, drawn on a smaller scale, and

Figure 5 is a view similar to Figure 4 of the other combined joint chair and fish plate.

Referring more in detail to the drawings, 5 indicates the meeting ends of the rail sections to be joined, and in accordance with the present invention, the same are bolted to-

gether by means of bolts 6 passing through the webs of the same and through the fish plate portions 7 and 8, respectively, of the combined chairs and fish plates shown respectively at 9 and 10 in Figures 4 and 5.

The fish plate portion 7 is of a form to engage the ball of the rail as at 11 and has an upwardly extending flange 12 whose ends are bevelled as at 13 so as to extend below the upper surfaces of the balls of the rail for thereby providing inclined surfaces between a relatively long flat surface, it being understood that the flat surface is slightly above the plane of the upper surfaces of the balls of the rail so that when the car wheels approach the joint they are elevated by the fish plates 7 for bridging the joint without the usual objectionable pounding. In this way the depression of one rail end below the other which actually causes the pounding, is prevented and this is also insured by reason of further construction which will presently become apparent.

The fish plate members or portions 7 and 8 each carry a relatively wide base 14 which is longitudinally grooved at its inner side as at 15 for reception of a base flange of the rail, the base 14 thereby providing a chair adapted to rest upon the upper surface of the ties. In order to insure sustaining of the weight upon the fish plate portion 7 the latter is braced as at 16 by means of transversely extending braces provided between the upper surface of the base 14 and the outer surface of the fish plate portion 7.

The base 14 of the member 9 is divided into three uniformly spaced sections, and between each two of the sections is a dependent member 17 which has a transverse opening 18 adapted to be aligned with a similar opening 19 provided in each of the similar dependent members 20 provided on the base of the member 10.

As shown in Figures 1, 3, 4 and 5, the sections of the bases 14 of the members 9 and 10 project outwardly a considerable distance beyond the members 17 and 20 so as to provide a relatively wide bearing upon the ties, and as the members 17 and 20 will project downwardly between adjacent sides of the ties, longitudinal creeping of the rail will be effectively prevented.

For assisting in preventing longitudinal creeping of the rails and for preventing spreading of the latter, the outer edges of the sections of the bases 14 are provided

with suitable notches 21 through which the usual spikes may be driven into the ties.

Suitable bolts 22 are passed through the aligned openings 18 and 19 so as to assist the bolts 6 in maintaining the joint assembled and for assisting to sustain the weight imposed upon the rails thereby preventing the above-mentioned depression of one rail end below the other.

10 It will be found that a rail joint constructed in accordance with the above will be characterized by having a relatively long period of usefulness without requiring repair or renewal of parts, and lateral tilting 15 of the rails as well as longitudinal creeping and spreading thereof will be effectively prevented so that loss of life from wrecks caused through these sources will be greatly minimized.

20 Minor changes may be made without departing from the spirit and scope of the invention as claimed.

What I claim as new is:

25 A rail joint including a pair of cooperating members, each member being formed of a relatively long casting provided in the

central portion and at the ends with tie engaging extensions beyond the edge of the base flanges of the rails received in said members, said casting having cooperating 30 base flange receiving recesses, upwardly extending walls on said members formed for engagement with the underside of said rail head, one of said members having a wheel bearing flange extending from the upwardly extending wall bevelled at the ends thereof, and stress receiving sections between the wheel flange, side walls, and tie engaging extensions for distributing stress to said extensions in line with the central portion thereof 40 and having spike receiving notches for receiving the spikes to secure the member to the respective ties, said members having portions depending below and between the tie extensions, securing means connecting the 45 members carried by said depending portion, and securing elements connecting the upwardly extending walls and the rails for assembling the joints.

In testimony whereof I affix my signature.

EVERT E. SWIFT.
